CLAIM

The ornamental design for a compact generator, as shown and described.

DESCRIPTION

FIG. 1 is a perspective view of the compact generator;

FIG. 2 is a front view of the compact generator;

FIG. 3 is a back view of the compact generator;

FIG. 4 is a right side view of the compact generator;

FIG. 5 is a left side view of the compact generator;

FIG. 6 is a top view of the compact generator; and,

FIG. 7 is a bottom view of the compact generator.

The broken lines are included for the purpose of illustrating environmental structure and form no part of the claimed design.
